JOHN J. MEEHAN, OF WASHINGTON, DISTRICT OF COLUMBIA, ASSIGNOR OF ONE-HALF TO
GUSTAV G. LOEHLER, OF WASHINGTON, DISTRICT OF COLUMBIA.

LID-LIFTER.

No. 904,346.

Specification of Letters Patent.

Patented Nov. 17, 1908.

Application filed January 6, 1908. Serial No. 409,555.

To all whom it may concern:

Be it known that I, JOHN J. MEEHAN, a citizen of the United States, residing at Washington, in the District of Columbia, 5 have invented certain new and useful Improvements in Lid-Lifters; and I do hereby declare the following to be a full, clear, and exact description of the invention, such as will enable others skilled in the art to which 10 it appertains to make and use the same.

This invention relates to improvements in lid lifters.

A general objection to articles of this description is that there is no positive interlock between the lifter and the lid. In the ordinary construction, the lifter is simply inserted in a recessed portion of the lid with its end extending in a recessed portion of the lid with its end extending beneath a projection 20 over the recess so that the lid is supported by the lifter by the weight of the lid causing a binding action therebetween. With lifters of this character however, it often happens, especially in cases of stove 25 lids, that the said binding action is destroyed, perhaps by a jolt, and consequently the lid is dropped, an accident that frequently results in breaking the lid and also in personal injury.

One of the objects of the present invention, therefore, is to overcome this objection by providing more positive interlocking means between the lifter and lid, and broadly the invention resides in the employ- 35 ment of a handle with a gripping jaw having spaced depending projections, one of said projections inclining towards the other.

While the invention is not restricted to the exact details shown and described, nor sim- 40 ply to the uses referred to, still for the purpose of disclosure reference is had to the accompanying drawings illustrating practical embodiments of the invention and the particular features of novelty will be more 45 succinctly pointed out in the claims.

In the drawings:—Figure 1 is a sectional elevation showing the preferred form of my invention with relation to stove lid lifters. Fig. 2 is a similar view showing a slightly 50 modified construction. Fig. 3 is a fragmentary perspective view of the jaw end of the lifter shown in Fig. 2. Fig. 4 is a sectional elevation showing a little different form of lid, and in this view the lid is shown as

associated with a man hole. Fig. 5 is a fragmentary plan view of the lid shown in Fig. 4, and Fig. 6 is a fragmentary sectional view illustrating an improved application of the invention as applied to a one-hole lid.

1 designates the top of a stove and 2 a lid 60 for one of the openings thereof.

In manufacturing lids for particular use with the present invention, it is desirable that the lids be cast in the form shown in Fig. 1, wherein 3 designates a thickened 65 portion in which are formed the forward and rear recesses, 4 and 5, spaced apart by the vertical or central projection 6. One of these recesses at least, is so disposed as to extend towards the other to form a locking 70 shoulder. In the drawings, the forward recess 4, is so illustrated forming the cavity 7, and the shoulder 8. In Fig. 1 the rear recess is also shown as extending toward the forward recess 4, forming a shoulder 9, which 75 however is not so pronounced as the shoulder 8. The lifter 10 for use with this particular form of lid is provided at its lower end, preferably, with the solid base integral member 11, having downwardly approaching lugs 12 and 13, which lugs may be of any suitable contour at their edges. The forward lug 12, inclines rearwardly and is 80 preferably curved or of hook shape, the line of curvature being such that when in the position shown in full lines in Fig. 1, the point of the hook is slightly distant from the wall of the recess but projects centrally beneath the shoulder 8, to prevent upward displacement. The rear lug 13, is shown as inclining 90 inwardly toward the forward lug 12, to form a bevel contact as at 14, with the rear face of the portion 6.

In the construction shown in Figs. 2 and 3 the arrangement is substantially similar 95 excepting that the forward face of the shoulder 8^a simply inclines downwardly and rearwardly without forming the underlying cavity, 7. Also the rear portion 9^a is provided with a beveled face inclining rearwardly and downwardly, or in an opposite direction to that shown in Fig. 1. Similarly the construction of lifter is slightly modified to suit these conditions, that is to say, the forward hook or lug 12^a has a lesser curvature and the rear lug 13^a inclines rearwardly 100 or in the same direction as the forward lug forming a rearwardly inclining beveled face 105

to engage the beveled face of the portion 9^a to form a friction connection therewith, as at 14^a.

In Figs. 4 and 5, the lid is simply shown 5 as provided with the two openings 15, passing through the lid, and adjacent one of these openings is formed a depending portion 16 coöoperating with the lifter after the same fashion as the rear beveled faces of the 10 central projection 6.

In operation the form of lifter shown in Fig. 1 is applied to the lid in substantially the position indicated by dotted lines, in which position the end of the hook 12 will 15 be disposed under the shoulder 8, but resting against the upper wall of the cavity 7. In this position of course, the lug 13 will be outside of the recess 5. When the handle portion of the lifter is forced downwardly 20 therefore, the lifter will pivot on the shoulder 8 and, as the distance from the inside lower end of the lug 13 to the inside curve of the hook 12 is greater than the distance 25 between the shoulders 8 and 9, it will follow that the lug 13 will swing past the shoulder 9 but will bind against the beveled surface as before described, drawing the hook 12 snugly against the shoulder 8 in the position shown in full lines in Fig. 1. In this position 30 it will be seen that there is a positive interlock between the lid and the lifter which will not be destroyed without swinging the lifter around again to the position shown in dotted lines.

35 From the foregoing the operation with relation to Figs. 2 to 4 will be apparent. As to Fig. 6, it will be seen that with a one-hole lid and with the lifter in the position illustrated, upon the downward movement of 40 the handle the rear lug 13^b will engage the top of the stove and act as the fulcrum of a lever until the inner face of the rear lug engages the outer edge of the lid when the lid may be lifted as heretofore described.

45 What I claim is:—

1. A lid lifter provided at its lower end with a gripping jaw comprising a base portion and a pair of depending lugs, the lower end of one of said lugs inclining downwardly and towards the other lug, said lugs being 50 adapted to be placed in depressed portions of a lid, substantially as described.

2. A lid lifter provided at its lower end with a gripping jaw comprising a base portion and a pair of depending lugs, the lower 55 end of one of said lugs being curved and inclining downwardly and towards the other lug, said lugs being adapted to be placed in depressed portions of a lid, substantially as described. 60

3. A lid lifter provided with a gripping jaw comprising a base portion and a depending rear lug and a forward lug rearwardly inclining in one direction only, said lugs being adapted to be placed in depressed portions of a lid, substantially as described. 65

4. A lid lifter provided with a gripping jaw comprising a base portion and a rearwardly inclining forward lug forming a hook and a downwardly projecting rear lug, 70 said lugs being adapted to be placed in depressed portions of a lid, substantially as described.

5. The combination of a lid having recesses separated by a vertical projection, and one edge of said projection extending over one of said recesses forming a shoulder with a lifter provided with a gripping jaw having a pair of depending lugs, one of said lugs inclining rearwardly and adapted to engage 80 beneath said shoulder, and the other of said lugs being adapted to engage the face of said vertical projection on the opposite side of said shoulder, substantially as described.

In testimony whereof, I affix my signature, 85 in presence of two witnesses.

JOHN J. MEEHAN.
